UNITED STATES PATENT OFFICE.

RUDOLPH VUILLEUMIER, OF NEW ROCHELLE, NEW YORK, ASSIGNOR TO THE SAFETY CAR HEATING AND LIGHTING CO., OF NEW YORK, N. Y., A CORPORATION OF NEW JERSEY.

CAR-AXLE POWER-TRANSMITTING MECHANISM.

1,168,446.

Specification of Letters Patent.

Patented Jan. 18, 1916.

Application filed January 10, 1912. Serial No. 670,383.

To all whom it may concern:

Be it known that I, RUDOLPH VUILLEUMIER, a citizen of the United States, residing at New Rochelle, in the county of Westchester and State of New York, have invented certain new and useful Improvements in Car-Axle Power-Transmitting Mechanism, of which the following is a full, clear, and exact description, such as will enable others skilled in the art to which it appertains to make and use the same.

This invention relates to car axle power transmitting mechanism, and with regard to certain more specific features thereof, to mechanism for efficiently driving a car-lighting generator from a car axle throughout all variations in speed of the latter.

One of the objects of the present invention is to provide a simple and compact construction of the above character.

Another object is to eliminate the shocks and excessive strains upon the driving belt and the bearings of the driven member.

Another object is to reduce slipping of the belt.

A further object is to provide a practical and efficient mechanism of the above character which will be cheap to manufacture and durable in construction.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of this invention—Figure 1 is a plan view of the complete apparatus; Fig. 2 is an end elevation of the mechanism shown in Fig. 1; Figs. 3 and 4 are detail views in plan and elevation of a preferred form of portion of driving belt; and Figs. 5 and 6 are similar views of a modification.

Similar reference characters refer to similar parts throughout the different views of the drawings.

Referring now to these drawings in detail

and more particularly to Figs. 1 and 2, 1 denotes a car truck of any desired construction, preferably of the cast steel type, having a depressed end transom 2, and provided with suitable journals, not herein shown, for an axle 3 connecting wheels 4. Secured to each side of the truck is a supporting bar 5 having an outwardly turned ear 6. Adjustably mounted upon each of these bars 5 is a stirrup 7 having a lug 8 which is connected by means of a bolt 9 with the ear 6. It is quite clear that by turning this bolt 9 the position of the stirrups 7 may be adjusted longitudinally of the truck. Suitable nuts and lock nuts 10 maintain the desired adjustment. The stirrups which engage both sides of the supporting member 5 are provided with bolts 11 passing through slots 12 in the supporting member, which not only prevent an upward removal of the stirrup, but also limit its range of adjustment and act as an additional securing means for maintaining adjustment. The stirrups 7 support a transverse rod 13 passing through a sleeve 14 connected directly with the casing of a generator 15. Clamping means 16 at each end of the sleeve 14 determine the transverse adjustment of the generator.

The lower part of the generator casing is provided with a lug 17 to which is swiveled a threaded bolt 18, the free end of which passes through a sleeve 19 trunnioned at 20 in a support 21 depending from the car truck. Lock nuts 22 at each side of the sleeve 19 maintain the desired adjustment.

It will be noted that there are two means permitting longitudinal adjustment of the generator casing; the upper one including the stirrups 7 may be considered an initial or approximate adjustment, while the lower one last above described may be considered an auxiliary or final adjustment, being much simpler and easier to manipulate. Although the generator is in fixed position a relative movement of the generator and axle is permitted, due to its position on the truck.

Although the generator has been shown in operative relation to the car axle by being mounted upon a car truck, it will be

understood that this is for purposes of illustration and the invention is not to be limited to this construction, but comprehends attaining the same object by mounting the generator in other relationships.

The generator is provided at one end of its armature shaft with a flanged pulley 23 in substantial alinement with a second pulley 24 mounted upon the axle 3. The pulley 24 is preferably wider than the pulley 23, so that a fine adjustment of the transverse position of the generator is unnecessary in order to insure perfect alinement for an endless elastic connecting member, herein-after termed a belt 25 connecting these pulleys. This belt, a section of which is shown in detail views Figs. 3 and 4, is preferably composed of a strip of belting 26 of leather or other material having a high coefficient 10 of friction, which is first longitudinally compressed in any desired manner before being secured at a plurality of points by means of rivets 27 to a plurality of sheet steel strips or plates 28 copper plated to 20 prevent rusting. By compressing the belting longitudinally it is thereby permitted to expand only within its elastic limit. The stress on the steel is never, under normal conditions, sufficient to exceed this limit. As 30 herein shown, these sheet steel strips are four in number, being arranged in upper and lower or superimposed pairs 29, 30. The upper pair is provided with inwardly extending cuts or slits 31 alternating with 35 similar slits 32 extending inwardly from the opposite side.

A space is provided between each pair of slits to accommodate the rivets 27. It will be noted that these slits do not extend all 40 the way across, but only partially across, so that the strip is cut into zigzag form, thereby permitting a longitudinal extension thereof, as well as a transverse bending. The under set or pair of plates 30 is similarly cut, yet the cuts alternate with those 45 in the upper set so that the cuts only partially register. In other words, the cuts or slits 31 in the plates 29 extend inwardly from one side of the belt, while the slits 33 in the pair of plates 30 immediately there-beneath extend inwardly from the opposite side. The same way the slits 34 in the pair 50 of plates 30 extend from the opposite side from the slits 32 immediately thereabove. The ends of these pairs of steel plates may 55 be considered as being L-shaped, so that when placed adjacent each other they will connect along the line 35. The underneath pair of plates 30 are similarly shaped, but their point of connection is offset in relation 60 to the upper pair, whereby the adjacent ends meet at the line 36. In this way the belt is of substantially uniform strength.

The belt is preferably constructed in substantially the proportions shown in the

drawings, as these proportions are believed to be more advantageous, although of course it is to be understood that they may be varied, if desired, and preferably should be varied if different materials than those herein specified are used. The purpose of using substantially the dimensions herein shown is to so proportion materials that excessive pressure upon the driving and driven pulleys may be eliminated when running at full speed, for the pressure upon the pulleys will thus vary inversely with the rate of rotation. The centrifugal force exerted upon the belt will tend to move the belt outwardly away from the surface of the pulley, thereby relieving the pressure upon the bearings of the generator as well as reducing the effective pull of the belt. It may also be noted that if the generator should be cut in at a speed of twelve miles per hour with full load and the same load maintained as the speed increases, the armature torque will decrease, and at a speed of sixty miles per hour will amount to about one-fifth of the torque of the twelve mile speed, thus ordinary apparatus giving a belt pressure five times greater than necessary. Therefore, by rigidly mounting the generator as herein disclosed the pressure upon the driving pulley decreases as the speed increases, due to the increase in centrifugal action of the belt, and by proportioning the materials used the excessive pressure upon the pulleys with increasing speed will be almost entirely eliminated.

In Figs. 5 and 6 there is shown a modified form of belt which comprises pairs of steel plates 29 and 30 substantially the same as those above described. The under pair of plates 30 is provided at regular intervals 105 with channel bars 37, each containing an aluminum block 38 held in place by means of the rivets 27. Other materials having a high coefficient of friction may be used, if desired, although aluminum has advantages, due to its lightness and the fact that it will 110 not rust.

It is thus seen that this invention provides a simple and practical form of car axle power transmitting mechanism adapted 115 to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a 125 limiting sense.

It is also to be understood that the language used in the following claims is intended to cover all of the generic and specific features of the invention herein described 130

and all statements of the scope of the invention, which, as a matter of language, might be said to fall therebetween.

Having described my invention, what I claim as new and desire to secure by Letters Patent is:

1. In an apparatus of the character described, in combination, a car truck, a generator suspended therefrom, means for adjustably securing said generator in fixed position, a pulley on the generator, a second pulley on an axle of the truck, and an elastic belt connecting said pulleys and adapted to drive the generator as the axle rotates, said belt being composed of materials so proportioned that an excessive pressure on the driving pulley is eliminated.
2. In an apparatus of the character described, in combination, a car truck, a generator suspended therefrom, means for adjustably securing said generator in fixed position, a pulley on the generator, a second pulley on an axle of the truck, and an elastic belt connecting said pulleys and adapted to drive the generator as the axle rotates, said belt being composed of a strip of belting and an elastic strip of steel.
3. In an apparatus of the character described, in combination, a car truck, a generator suspended therefrom, means for adjustably securing said generator in fixed position, a pulley on the generator, a second pulley on an axle of the truck, and an elastic belt connecting said pulleys and adapted to drive the generator as the axle rotates, said belt being composed of an inner strip of belting and an outer strip of sheet steel.
4. In an apparatus of the character described, in combination, a car truck, a generator suspended therefrom, means for adjustably securing said generator in fixed position, a pulley on the generator, a second pulley on an axle of the truck, and an elastic belt connecting said pulleys and adapted to drive the generator as the axle rotates, said belt being composed of an inner strip of belting and an outer strip of sheet steel, said leather being longitudinally compressed before being secured to the strip of steel.
5. In an apparatus of the character described, in combination, a car truck, a generator suspended therefrom, means for adjustably securing said generator in fixed position, a pulley on the generator, a second pulley on an axle of the truck, and an elastic belt connecting said pulleys and adapted to drive the generator as the axle rotates, said belt being composed of an inner strip of belting and an outer strip of sheet steel, said strip of steel being provided with cuts to permit an elastic extension thereof.
6. In an apparatus of the character described, in combination, a car truck, a generator suspended therefrom, and a belt connecting the generator with an axle of the

truck, said belt being composed of a plurality of layers of belting and sheet steel, the steel being copper plated to prevent rusting.

7. In an apparatus of the character described, in combination, a car truck, a generator suspended therefrom, and a belt connecting the generator with an axle of the truck, said belt being composed of an inner layer of material having a high coefficient of friction and an outer layer of relatively strong elastic material.

8. In an apparatus of the character described, in combination, a car truck, a generator suspended therefrom, and a belt connecting the generator with an axle of the truck, said belt being composed of an inner layer of material having a high coefficient of friction and an outer layer of non-rustable material provided with means to permit an elastic extension thereof.

9. In an apparatus of the character described, in combination, a car truck, a generator adjustably supported thereby, a driven member connected with the generator, and a belt between the driven member and an axle of the truck adapted to drive the generator, said belt including a reinforcing member having means permitting an elastic extension thereof.

10. In an apparatus of the character described, in combination, a car truck, a generator adjustably supported thereby, a driven member connected with the generator, and a belt between the driven member and an axle of the truck adapted to drive the generator, said belt including a plurality of sheets of steel connected to each other and having means associated therewith to permit an elastic extension thereof.

11. In an apparatus of the character described, in combination, a car truck having an axle, a pulley mounted on said axle, a generator supported from said truck, a second pulley directly connected with said generator, and an endless elastic belt extensible within its elastic limit on said pulleys for driving said generator.

12. In an apparatus of the character described, in combination, a car truck having an axle, a pulley mounted on said axle, a generator supported from said truck, a second pulley directly connected with said generator an endless elastic belt on said pulleys for driving said generator, said belt including resilient metal members, and friction material between said members and the surface of the pulleys.

13. In an apparatus of the character described, in combination, a car truck, a generator adjustably supported thereby, a driven member connected with the generator, a belt between the driven member and an axle of the truck adapted to drive the generator, said belt including metallic mem-

- bers having means permitting an elastic extension thereof, and means having a high coefficient of friction adapted to be interposed between the inner surface of the members and the surface of the driving and driven members.
14. In an apparatus of the character described, in combination, a car truck, a generator adjustably supported thereby, a driven member connected with the generator, and a belt between the driven member and an axle of the truck adapted to drive the generator, said belt including a longitudinally compressed strip of leather and a sheet steel member secured thereto at a plurality of points.
15. In an apparatus of the character described, in combination, a car truck, a generator adjustably supported thereby, a driven member connected with the generator, and a belt between the driven member and an axle of the truck adapted to drive the generator, said belt including a longitudinally compressed strip of fibrous material and a non-rustable plate secured thereto at a plurality of points, said plate having alternating slits cut in from opposite sides thereof extending partially across the plate to permit an elastic extension thereof.
16. In an apparatus of the character described, in combination, a car truck, a generator adjustably supported thereby, a driven member connected with the generator, and a belt between the driven member and an axle of the truck adapted to drive the generator, said belt comprising a plurality of superimposed sheet steel plates, said plates having partially registering slits cut in alternately from opposite sides thereof to permit a zigzag expansion of the belt.
17. In an apparatus of the character described, in combination, a car truck, a generator adjustably supported thereby, a driven member connected with the generator, and a belt between the driven member and an axle of the truck adapted to drive the generator, said belt comprising a plurality of metal sheets arranged in pairs and secured to each other at a plurality of points, each pair being provided with a plurality of slits extending inwardly from the sides thereof partially across the sheet and alternating with similar slits cut from the opposite side, the slits in one pair of plates only partially registering with the slits of another pair.
18. In an apparatus of the character described, in combination, a car truck, a generator adjustably supported thereby, a driven member connected with the generator, a belt between the driven member and an axle of the truck adapted to drive the generator, said belt comprising a plurality of sheets of steel arranged in pairs and secured to each other at a plurality of points,
- each pair being provided with a plurality of slits extending inwardly from the sides thereof partially across the sheet and alternating with similar slits cut from the opposite side, the slits in one pair of plates only partially registering with the slits of another pair, and material having a high coefficient of friction adapted to be interposed between the inner surface of the sheets of steel and the driving and driven members.
19. In an apparatus of the character described, in combination, a car truck, a generator adjustably supported thereby, a pulley connected with the generator, a belt between the pulley and an axle of the truck to drive the generator, said belt comprising a plurality of sheets of steel arranged in pairs and secured to each other at a plurality of points, each pair being provided with a plurality of slits extending inwardly from the sides thereof partially across the sheet and alternating with similar slits cut from the opposite side, the slits in one pair of plates only partially registering with the slits of another pair, and a strip of longitudinally compressed belting secured to said plates at a plurality of points whereby the generator may be driven at full load with a tensile stress in the belt less than the elastic limit of the materials of which the belt is composed.
20. In an apparatus of the character described, in combination, a car truck, a generator, a pulley on the generator, a pulley on an axle of the truck, and an elastic belt connecting said pulleys and adapted to drive the generator as the axle rotates, said belt comprising a strip of friction material and an outer reinforcing elastic strip.
21. In an apparatus of the character described, in combination, a car truck, a generator having a fixed relation thereto, a belt connecting the generator with the axle of the truck adapted to drive the generator under full load with a tensile stress in the belt less than its elastic limit.
22. In an apparatus of the character described, in combination, a driving pulley, a driven pulley, a generator operatively connected to said driven pulley and secured in a normally fixed relation to said driving pulley, and a belt connecting said pulleys and adapted to drive the generator as the axle rotates, said belt comprising materials so constructed and related to each other that an excessive pressure on the said pulleys is eliminated as the speed thereof increases.
23. In an apparatus of the character described, in combination, a generator, a pulley thereon, a driving pulley, and a belt connecting said pulleys, said belt comprising a plurality of superimposed sheet steel plates having partially registering slits cut in alternately from opposite sides thereof to permit expansion of said belt.

24. In an apparatus of the character described, in combination, a generator, a pulley thereon, a driving pulley, a belt connecting said pulleys, said belt including members constructed to permit an elastic extension thereof, and means having a high coefficient of friction interposed between the inner surface of the metallic members and the surfaces of the pulleys.
- 10 25. In an apparatus of the character described, in combination, a generator, a pulley thereon, a driving pulley, and a belt connecting said pulleys, said belt comprising a layer of longitudinally compressed material and a plurality of members constructed to permit elastic extension thereof.
- 15
26. In an apparatus of the character described, in combination, a driving pulley, a driven pulley, a generator operatively connected to the driven pulley, and a driving belt connecting said pulleys comprising resiliently connected parts for rendering said belt longitudinally extensible and contractible under the influence of centrifugal force as the speed of said pulley varies. 20 25

In testimony whereof I affix my signature, in the presence of two witnesses.
